GASEOUS ELECTRIC DISCHARGE DEVICE

Georg Gaidies, Berlin-Pankow, Germany, assignor
to General Electric Company, a corporation of
New York

Application September 27, 1932, Serial No. 635,037
In Germany November 17, 1931

2 Claims. (Cl. 176—122)

The present invention relates to gaseous electric discharge devices generally and more particularly the invention relates to such devices of the positive column type in which metal vapor 5 constitutes the gaseous atmosphere or is a component of the gaseous atmosphere.

The object of the invention is to provide a high intensity light source being a gaseous electric discharge device useful in television, spectrometry, beacon work, or the like. Still further 10 objects and advantages attaching to the device and to its use and operation will be apparent to those skilled in the art from the following particular description and from the appended 15 claims.

In accordance with this object the device comprises an elongated container having a gaseous atmosphere therein and an anode and a cathode sealed therein. Said cathode is an elongated 20 hollow chamber having a reentrant tube part forming a contracted opening in the direction of the anode and the longitudinal axis of said tube part is coincident with the longitudinal axis of the container of the device. Said anode is an 25 annular disk and the opening therein is concentric with the open tube part of said cathode. The positive column discharge between said anode and said cathode thus extends along, and is visible end-on through the opening in said 30 anode, in the direction of the longitudinal axis of the container. The length or depth of said hollow cathode is greater than twice the distance between said cathode and the anode. A vaporizable metal is located in the interior of said 35 cathode. By virtue of the particular shape of the cathode, and the arrangement of the anode and cathode the greater part of the length of the positive column discharge is located in the contracted opening in said cathode and the heat resulting 40 from said discharge and from the glow discharge in said cathode plus the heat resulting from the cathode drop raises said cathode to a comparatively high temperature, but not to an incandescent temperature however, which causes 45 a heavy vaporization of the vaporizable metal in said cathode which vapor conducts the electric discharge in the device. Having the above structure and operating in the above manner the gaseous electric discharge device is a spot light source 50 of high intrinsic brilliancy.

In the drawing accompanying and forming part of this specification an embodiment of the invention is shown in a sectional side elevational view.

55 Referring to the drawing the device comprises

an elongated cylindrical container 1 having a gaseous atmosphere therein and having electrodes 2 and 6 sealed therein. Said electrode 2 is an elongated, hollow chamber, the top cover 4 thereof having a reentrant tube 5 forming a contracted opening. The longitudinal axis of said tube 5 is coincident with the longitudinal axis of said container 1. Said electrode 2 is the cathode and is mounted on and supported by current inlead 3 sealed into said container 1. Electrode 6 is an annular disk, the diameter of the opening therein is approximately the same as the diameter of the opening in said tube 5 and the center of said opening lies in the longitudinal axis of said tube 5. Said electrode 6 is the anode and is supported by current inlead 7 sealed into said container 1.

A vaporizable metal, such as sodium, caesium or cadmium, is located in the interior of said electrode 2. The length or depth of said electrode 2 is greater than twice the distance between said electrode 6 and the cover 4 of said electrode 2. Thus, during the operation of the device, the heat resulting from that part of the positive column discharge in said tube 5 and the glow discharge in said cathode 2 plus the heat developed by reason of the cathode drop heats up said electrode 2 to a high temperature, but not to an incandescent temperature, which causes a strong vaporization of the vaporizable metal in said electrode 2 which vapor actively participates in conducting the electric discharge device.

Take, for example, an electric discharge device having a gaseous filling comprising a mixture of neon and helium at a pressure of 3 mm. in which the distance between the anode 6 and the cathode 2 is 10 mm. and in which the cathode 2 is 60 mm. in length and 20 mm. in diameter. With a current of 50 milliamperes the cathode 2 is heated to a temperature of approximately 200° to 300° C. The vaporizable metal, such as sodium, in said cathode 2 is vaporized at this temperature and the spectrum of the emitted light is strong in the characteristic color of the sodium vapor. The brilliant positive column discharge in said tube 5 is visible end-on through the opening in said electrode 6.

Where desired the difference between the outer diameter of said electrodes 2 and 6 and the inner diameter of said container 1 is less than the mean free path of the ionized gas to prevent the development of the gaseous electric discharge on the external walls of said electrodes 2 and 6. The part 8 of said container 1 is made of ultra violet transmitting or other special glass where de-

- sired. The smaller the diameter of the opening in the reentrant tube 5 the more concentrated is the positive column discharge therein, which increases the brilliancy of the light source, and said tube 5 guides the electric discharge along the longitudinal axis of the container and prevents sputtered, unvaporized metal particles from escaping from the interior of said electrode 2 and depositing on the walls of said container 1.
- 10 The development of undesired deposits of condensed metal vapor on the walls of said container 1 is prevented by maintaining the walls of said container at a temperature higher than the condensation temperature of said metal vapor by the use of a double walled container, the space between said walls being evacuated or filled with a heat absorbing gas, such as argon, or a heat absorbing jacket, or a heating element placed around said container 1.
- 15 While I have shown and described and have pointed out in the annexed claims certain novel features of the invention, it will be understood that various omissions, substitutions and changes in the forms and details of the device illustrated 20 and in its use and operation may be made by those skilled in the art without departing from the broad spirit and scope of the invention.
- 25 What I claim as new and desire to secure by Letters Patent of the United States is:—
- 30 1. An electric discharge device comprising a

container, electrodes sealed therein, a gaseous atmosphere therein, at least one of said electrodes being a hollow cathode having an elongated re-entrant tube part close to the other electrode and containing a vaporizable material, said tube part being a contracted opening for said cathode, another of said electrodes being an annular disc anode the center of the opening therein lying in the longitudinal axis of said tube part, the length of said cathode being greater than twice the distance between said anode and said cathode, the greater part of the discharge path between said electrodes being in said cathode.

2. An electric discharge device comprising a 15 container, electrodes sealed therein, a gaseous atmosphere therein, at least one of said electrodes being a hollow cathode having an elongated re-entrant tube part and containing sodium, said tube part being a contracted opening for said cathode, another of said electrodes being an annular disc anode the center of the opening therein lying in the longitudinal axis of said tube part, the length of said cathode being greater 20 than twice the distance between said anode and said cathode, the greater part of the discharge path between said electrodes being in said cathode.
